ATTORNEYS

UNITED STATES PATENT OFFICE

GUY CARPENTER, OF NEW YORK, N. Y.

SPARK ARRESTER

Application filed April 1, 1924. Serial No. 703,391.

My invention relates to the art of separating and collecting the particles of solids in the products of combustion, in locomotive engines, and is a further development of my previous inventions set forth and described in my application for Patent #693,185, filed Feb. 16, 1924, and my application #693,186, filed Feb. 16, 1924.

As in my former inventions the object is attained by imparting a strong centrifugal force upon the gases as they travel from the fire box to the stack exit and providing means to separate the solids from the gases and collect them in a collecting chamber from which they may be removed. In this invention, as distinguished from my former ones, I locate my principal functioning elements in a more advantageous position, and construct a stack chamber surrounding the stack.

My invention will be easily and clearly understood by anyone skilled in the art, by reference to the accompanying drawings, in which:

Fig. 1 shows a longitudinal sectional view of the forward end of a locomotive engine fitted out with my device, and

Fig. 2 shows a transverse sectional view taken on the line 2—2, in Fig. 1.

Referring to the accompanying drawings, the reference numeral 10 indicates the fire tubes of a locomotive engine, the numeral 11 the smoke box, the numeral 12 the smoke stack and the numeral 13, the exhaust jet thereof.

In the smoke box 11 and between the smoke stack 12 and the forward end of the smoke box, I have formed a chamber 14 bounded by two spaced members 15 and 16, a base 17, and a part of the inner wall of the smoke box 11. In this chamber I have mounted an outer cylinder 18, spaced from the inner surface thereof, and an inner cylinder 19, and a helically formed member 20, the blade thereof extending from the inner surface of the outer cylinder to the outer surface of the inner cylinder, is mounted between the cylinders. Baffles 21 are provided on the inner surface of the outer cylinder and openings 22 extend through the walls of the outer cyl-

inder, the openings being in close proximity to their attendant baffles. Obviously there is an opening 23 in the side member 15 and an opening 24 in the side member 16, these openings communicating with the spiral passage formed between the cylinders. An opening 25 is formed in the base 17 communicating with an exit passage 26, closed at the base of the smoke box 11, by a door 27.

The base 17 extends rearwardly, as shown, to a point between the stack 12 and the fire tubes 10, to a partition 28 which extends upwardly from this base separates the stack chamber 29, thus formed, from the smoke box 11. The jet 13 extends upwardly through the lower portion of the smoke box 11, and through the base 17, and is positioned centrally below the open lower end of the smoke stack 12.

By this construction a passage is formed leading from the fire tubes 10, below the smoke stack 12 (and separated therefrom) to the forward end of the smoke box, thence upwardly to the opening communicating with the spiral passage, through the spiral passage and the opening at the other end thereof, into the stack chamber. Gases from the fire box must pass through this long passage to their exit through the stack, and before reaching the stack a strong centrifugal force has been imparted to them through the action of the exhaust jet which exerts a pulling force or suction through the spiral passage created by the helically formed member. This operates to throw the particles of solids, which invariably accompany the products of combustion, to the inner wall of the outer cylinder 18, where they are caught by the baffles 21 and conducted through the openings 22 in the cylinder to the collection chamber formed between the outer surface of the outer cylinder and the inner surface of the chamber 14, and fall to the bottom thereof. A tube 26 opens into the base 17, and a door 27 closes the outer end of the said tube. Through this tube 26 and door 27, solids which have been separated from the smoke may be removed.

The drawings illustrate a preferred form of construction and as I am aware, many different equivalent forms may be utilized with-

out departing from the spirit of my invention. I do not desire to be limited in the scope of my invention except as set forth in the appended claims.

Having thus described my invention what I claim and desire to secure by Letters Patent of the United States, is:

1. A spark arrester for locomotive engines employing a fire box, comprising a smoke stack; a smoke box; a stack chamber, mounted in the smoke box, and enclosing the lower end of the smoke stack; a cylinder, a second chamber adjacent the stack chamber, mounted in the forward end of the second chamber; a helically formed member, secured within said cylinder, the elements being so arranged as to cause the smoke from the fire box to pass through the smoke box and through the cylinder containing said helically formed member, before the smoke can reach the stack chamber and pass out through the smoke stack, substantially as shown and described.

2. A spark arrester for locomotive engines employing a fire box, comprising a smoke stack; a smoke box; a deflecting element mounted in the rear of the smoke stack; a longitudinal partition below the smoke stack, attached to and extending from the deflecting element to a point near the forward end of the smoke box; a pair of spaced, longitudinally mounted, cylinders, one within the other, above the longitudinal partition, and positioned between the smoke stack and the forward end of the smoke box, said outer cylinder having openings through its wall; and a helically formed member, secured between the inner wall of the outer cylinder and the outer wall of the inner cylinder, to form a spiral passage between said cylinders.
